(57) **CLAIM**

The ornamental design for a container assembly, as shown and described.

DESCRIPTION

FIG. 1 is an upper front perspective view of a container assembly showing our new design;

FIG. 2 is a lower front perspective view of the design of FIG. 1;

FIG. 3 is a front elevation view of the design of FIG. 1;

FIG. 4 is a top plan view of the design of FIG. 1; and,

FIG. 5 is a bottom plan view of the design of FIG. 1.

The broken lines shown in FIGS. 1–5 depict portions of the container assembly that form no part of the claimed design.
